TOTAL TAKING MECHANISM

Robert Anschütz, Zella-Mehlis, Germany, assignor to Mercedes Buromaschinen-Werke Aktiengesellschaft, Zella-Mehlis, Thuringia, Germany

Application January 16, 1939, Serial No. 251,257
In Germany February 12, 1938

4 Claims. (Cl. 235—59)

This invention relates to a total taking control means under control of the totalizer to select and actuate the type bars to print the amount standing in the totalizer and, in which the selector for the types to be printed is a cam shaft mounted to rotate in fixed bearings, and the operation of the types is controlled by setting members in a swinging frame operated by the driving member of the total taking control means.

The well known mechanism in this manner are improved according to the present invention by arranging intermediate members in the drive of the swinging frame, which intermediate members are operated by the driving member of the total taking mechanism. By these means, the construction of the mechanism, and particularly the coupling of the swinging frame with the driving member for the total taking control means, is much simplified.

In the drawings one form of construction according to the invention is illustrated by way of example as applied to a machine as described in patent application No. 146,897.

In the drawings:

Fig. 1 is an elevation, partly broken open, of a typewriting-calculating machine equipped with the invention, viewed from the left.

Fig. 2 is a perspective illustration showing several parts of the mechanism, viewed from the front and the left of the machine.

Fig. 3 is a detail.

The parts which are operated when total taking

Referring now to the drawings, and first to Fig. 1, a total taking key 2 is arranged in a bearing frame 1 of the machine.

The key bar 3 of the total taking key 2, as best seen in Fig. 2, is mounted to swing on a bar 4 secured in the bearing frame 1. A spring 5 holds an abutment 33 on the key bar 3 against the inner side of a locking bar 6 which is also secured in the bearing frame 1, defining the normal position of the key bar. A locking pawl 8 is mounted to swing about a screw 7 on the key bar 3 and a spring 9 holds a tooth 10 on the pawl against the outer side of the locking bar 6.

When the total taking key 2 is depressed, its key bar 3 turns clockwise and the tail end 12 of the bar raises a slide 13 which, operates a zero setting stop for the zero setting wheels in a column totalizer as described and illustrated in patent application Serial Number 146,897. At the same time, the tooth 10 of the pawl 8 engages in a groove 14 in the locking bar 6 holding the total taking key 2 depressed. The tail end 15 of

the pawl moves into active position with respect to an unlocking slide 16.

On a rotating shaft 25, of square cross-section with rounded edges are arranged a pair of cam plates 20 and 21. These cam plates 21, 22 are free to turn on said shaft 25. The cam plates 20, 21 and other parts, have been shown at some distance from each other in Fig. 2, for the sake of clearness. Rivets 18 extend through slots 19 in the two cam plates 20, 21 and their free ends support a clutching member 17 on which a slot 27 for their reception is arranged. A compression spring 22 is inserted in the slot 27 between a pin 28 in the cam plate 21, and the rivet 18 which is at the right. The spring holds the free end of the member 17 against the tail end 12 of the key bar 3 with a face 23 and in this position a hook 24 of the member 17 is clear of the teeth of a pinion 26 which is held against rotation on the shaft 25. In this position, the cam plates 20, 21 are arrested while the shaft 25 rotates freely.

The cam plates 20, 21 are rigidly connected to each other and by the torque the reaction of the spring 22 exerts on the pin 28, the cams 20, 21 are turned anti-clockwise together, and a roller 29 on the cam plate 20 is forced against the edge 30, Fig. 1, of a locking lever 31, defining the normal position of the cams. The locking lever 31, as shown in Fig. 2, has a boss 32 on the bar 4 and a spring 33 holds the front end of the lever against the upper side 34 of the locking bar 6.

Mounted to swing on the boss 32 of the locking lever 31 is a camplate lever 37 with its boss whose ends 35 and 36 project beyond the sides of the camplate lever, holding it against lateral displacement on the bar 4 between the key bar 3 of the total taking key 2, and the locking lever 31. A spring 39 connects a crooked lug 38 at the upper end of the camplate lever 37 to a pin 40 in the key bar 3. This spring turns the lever 37 clockwise and holds a roller 41 on a rivet 42 at the lower end of the camplate lever 37, or its arm 43 against the cam plate 20.

The lug 38 has an inclined edge 45 for cooperation with the front end 46 of a push rod. The camplate lever 37 and the push rod are not in operative connection, the push rod being elevated beyond the upper end of the lug 38.

The push rod consists of two parts 47 and 48 which are connected by screws 49 in elongated holes 50, and the rear part 48 is slotted at 51 and guided between sleeves 53 and 54 on a stud 52 in the left-hand frame plate of the machine. The rear end 73 of the part 48 is crooked to the left and curved at 74. This curved portion en-

gages the, also curved, front edge of an arm 76, and plates 77 on the arm hold the parts against lateral displacement. The boss 78 is secured on a shaft 79 and the shaft is held between the pointed ends of screws, not shown, in the right and left-hand side plates of the machine. A spring 82 which is attached to the arm 76 at its rear, and to a pin 83 in the left-hand side wall of the bearing frame 1 at its front end, holds the edge 75 of the arm 76 engaged with the rear portion 74 of the part 48.

The front part 47 of the rod slides in a slot 55 in a downwardly directed rib 56 of a comb 51 for guiding the actuating slides. The comb 51 is supported by a bracket 58 for the roller lock of the key bars in a typewriting keyboard 59 of the machine, which is secured in the frame of the machine by a bar 60. A spring eye 61 is inserted in the bar and supports one end of a spring 62 whose other end is attached to a pin 63 in the push rod part 47. The pull of the spring in the direction of the arrow 64, forces the rear end of the slot 51 against the stud 52, and the upper edge 65 of the push rod against the upper end 66 of the slot 55, defining the normal position of the push rod.

An unlocking slide 68 slides in another slot 67 in the comb 57 and springs 70, Fig. 1, hold a roller 69 at the lower end of the slide against the cam plate 21. A pin 71 moves through a hole 72 in the comb 57 when the unlocking slide 68 descends, and engages the upper edge of the push rod.

Secured on the shaft 80 carrying the arm 76 are the bosses 84 and 85 of a pair of forks 86 and 87 arranged whose openings 88 and 89 engage a stay 90 in a swinging frame comprising a side member 91 at the left which is pivoted about the stud 52, a side member 93 at the right which is pivoted about a stud 94 in the right-hand side plate of the machine, and another stay 92. The forks 86 and 87 are arranged within the frame near the ends of the stay 92.

The parts which have just been described, from the camplate lever 37 to the forks 86, 87 make up the intermediate members referred to in the introduction.

Setting members in the shape of ten bellcranks 95 only one of which is shown in Fig. 2, are mounted to swing on the stay 92 in the swinging frame, and spaced by sleeves 96. The shorter arms 99 of the bellcranks 95 are under the control of ten cams 98, Fig. 1, which are arranged helically on a cam shaft 97. Two more cams 98 have been shown in Fig. 1 which are provided for the duodecimal calculations required by the British system.

A link 101 is mounted to swing about a screw 100 near the upper end of each bellcrank 95 and is adjusted by a set screw 102 and an arcuate slot 103. Connecting rods 104 extend from the links 101 to the lower arms 105 of intermediate levers 106, Fig. 1. The intermediate levers which are mounted to swing about a shaft 107, throw type levers 108 against the platen 110 on the carriage 115 when turned clockwise.

The operation of the mechanism when total taking

As described, the key bar 3 of the total taking key 2 is turned clockwise on the bar 4 when the key 2 is depressed, and the pawl 8 moves with the key bar. Its tooth 10 engages in the groove 14 in the locking bar 6 and holds the key bar 3 depressed. The tail end 12 of the key bar 3 clears 75

the face 23 of the clutching member 17 whose tooth 24 is now forced in between the teeth of the pinion 26, so that now the cams 20 and 21 rotate—clockwise—with the shaft 25. At the beginning of a revolution, the unlocking slide 68 is allowed to descend under the action of its springs 70 by the cam 21, and its pin 71, descending through the hole 72 in the comb 57, bears against the upper edge 65 of the push rod and swings it clockwise about the stud 52 against its spring 62, placing the front end 46 of the rod in active position with respect to the incline 45 at the upper end of the camplate lever 37. While this occurs, the concentric portion of the cam plate 20 moves idly past the roller 41 at the lower end of the cam plate lever. The cam 21 is so shaped that upon further rotation of the cam plates the unlocking slide 68 at first remains in the position shown in Fig. 3, and the operative connection 45, 46 remains. Then the ascending portion 111 of the cam plate 20 swings the lever 37 anticlockwise about the boss 32 of the locking lever 31 against its spring 39. The incline 45 of the lever now pushes back the push rod in the direction of the arrow 112 against the spring 62 for about the length of its slot 51. The arm 76 and its shaft 80 are turned in the direction 112 against the spring 82. The edges 114 and 115 of the forks 86 and 87 engage below the stay 90 and turn the swinging frame clockwise about its pivots 52 and 94.

While this occurs, the zero setting operation is performed in the column totalizer and the cam shaft 97 is turned clockwise to present a cam 98, for instance, that for the number "5," to the arm 99 of the bellcrank 95.

When the swinging frame is turned clockwise, the bellcranks on the stay 92 are raised and the arm 99 of the corresponding bellcrank engages below the cam 98 of the value "5." The bellcrank turns anti-clockwise on the stay 92 and its link 101 pulls the connecting rod 104 to the rear in the direction of the arrow 112, Fig. 2. The corresponding intermediate lever 106 is swung clockwise about the shaft 107, and the type lever 108 of the value "5" is thrown against the platen 110.

Upon further rotation of the shaft 25, the elevated portion of the cam 20 allows the springs 39 and 62 to return the cam plate lever 37 and the push rod into the intermediate positions shown in Fig. 3, and the pull of the spring 82 returns the lever 76 and the shaft 80 on which it is mounted, into initial position. The forks 86 and 87 now return the swinging frame into its initial position, and the elevated portion of the cam plate 21 raises the unlocking slide 68 its pin clearing the upper edge 65 of the push rod and allowing the spring 62 to return the push rod into its inactive position in which the drive 45, 46 is interrupted.

In a similar manner, the remaining numbers of the value indicated by the column totalizer are typewritten and then the clutch 17, 25 is thrown out by the slide 16 descending on the pawl 8, throws its tooth 10 out of the groove 14 in the locking bar 6 as described in said patent application No. 146,897. When the cams 20, 21 have completed their revolution, the face 23 of the clutching member 17 is arrested by the tail end 12 of the key bar 3 and moves its tooth 24 clear of the teeth of the pinion 26. The cam shaft 97 also returns into its initial position, and all parts are now ready for another operation in the position illustrated in Fig. 1.

The object of so arranging the driving con-

nection between the cam plate lever 37 and the end 46 of the push rod that it is normally interrupted, is as follows:

If the operator by inadvertence depresses the total taking key 2 in any position of the paper carriage in which none of the column totalizers is in active position, the unlocking slide 68 cannot descend as it is, arrested by locking means 116, as illustrated in the Patent 1,862,240 for the slide 16. All the same, depression of the total taking key 2 starts the cam plates 20, 21 which operate the cam plate lever 37 but its edge 45 cannot act on the end 46 of the push rod. If there were a permanent connection, the number "0" would be typed upon depression of the key 2 since in the normal position, Fig. 1, the "0" cam 98 is in active position to the arm 99 of the corresponding bellcrank 95. The clutching-in of the cam plates 20, 21 by unintentional operation of the key 2 is broken by hand by which the slide 16 is moved down.

It should be noted that the expression "total taking" as used in the specification and the claims, includes any kind of total taking, for instance, subtotal taking.

Having now particularly described and ascertained the nature of our said invention and in what manner the same is to be performed, we declare that what we claim is:

1. In a combined typewriter and calculating machine, a power driven clutch, a total key for controlling the engagement and disengagement of said power driven clutch, a double drive cam operable by said power driven clutch, type levers, selecting means for determining the type lever to be operated during total taking operation, crank levers cooperating with said selecting means, in combination, connecting members rigidly connecting said type levers with said crank levers, a swinging frame for said crank levers, rocking members for rocking said swinging frame, said rocking members being operable by one part of said double drive cam and being connected with said swinging frame at remotely spaced points thereof to impart equal rocking forces to the opposite extremities of said swinging frame.

2. In a combined typewriter and calculating machine, a power driven clutch, a total key for controlling the engagement and disengagement of said power driven clutch, a two part double drive cam operable by said power driven clutch, an unlocking slide for total taking rendered operative by one part of said double drive cam, type levers, selecting means for determining the type lever to be operated during total taking opera-

tion, crank levers cooperating with said selecting means, in combination, connecting members rigidly connecting said type levers with said crank levers, a swinging frame for said crank levers, a rock-shaft, rocking members rigidly mounted on said rock-shaft for rocking said swinging frame, a spring urged member on said rock-shaft, controlling means for said rock shaft including a two part push rod interposed between 5 said clutch and said spring urged member, and a rocking lever, said push rod being adapted to be brought into driving connection in relation to said rocking lever by said unlocking slide for producing a driving connection between said 10 swinging frame and the other part of said double drive cam.

3. In a combined typewriter and calculating machine, a power driven clutch, a total key for controlling the engagement and disengagement 20 of said power driven clutch, a double drive cam operable by said power driven clutch, type levers, selecting means for determining the type lever to be operated during total taking operation, crank levers cooperating with said selecting 25 means in combination, a swinging frame for said crank levers, rocking members for rocking said swinging frame, said rocking members being operable by one part of said double drive cam, a spring urged member, a rock-shaft common to 30 said rocking members and said spring urged member, a two part push rod interposed between said clutch and said spring urged member, and guide plates on said spring urged member to secure one part of said push rod in lateral position.

4. In a combined typewriter and calculating machine, a power driven clutch, a total key for controlling the engagement and disengagement 40 of said power driven clutch, a double drive cam operable by said power driven clutch, type levers, selecting means for determining the type lever to be operated during total taking operation, crank levers cooperating with said selecting means, in combination, a swinging frame for said 45 crank levers, rocking members for rocking said swinging frame, said rocking members being operable by one part of said double drive cam, a spring urged member including a curved part, a rock-shaft common to said rocking member and said spring urged member, a two part push rod interposed between said clutch and said spring urged member, a rounded face on said push rod coacting with the curved part of said spring urged member.

ROBERT ANSCHÜTZ.
